ABSTRACT: For feeding wire or other elongate flexible stock along a predetermined path, apparatus comprising a constant feeder at one location along the path, an intermittent feeder farther along the path, a portion of the stock between said feeders being free to move in a direction transverse of the path, and a regulator in said portion for maintaining uniform tension in the stock, said regulator comprising a guide bearing on said portion and means yieldingly pressing the guide in said direction, said means including a chamber containing gas under pressure and an actuator responsive to said pressure for actuating said guide, whereby the guide can react quickly in response to rapid jerks of said feeder.

PATENTED JAN 19 1971

3,556,373

TENSIONING APPARATUS

This invention relates to apparatus for handling elongate, flexible stock such as wire, film, ribbon, etc., and more particularly to apparatus for maintaining uniform tension in the stock as it is fed into a machine intermittently. Heretofore it has been proposed to accomplish this result by providing a depending loop in the stock between the supply reel and the feeder and floating a weighted roller in the bottom of the loop. It has also been proposed to press a guide roller against a stretch of the stock with a spring. While these devices are satisfactory for relatively slow apparatus such as cinematographic cameras and projectors they are inadequate for apparatus in which the stock is advanced at high speed with quick jerks because the devices do not respond quickly enough to maintain the stock taut and also avoid damage to the stock. The problem is aggravated in apparatus in which the intermittent feeder slacks off the stock between successive advances, that is not only stops advancing the stock but permits the stock to move backwardly between advances.

Objects of the present invention are to maintain the tension in the entering stock more or less uniform even though the stock be advanced rapidly with quick jerks and even though the entering stock be slackened off between intermittent advances, and to avoid damage to the stock as a result of the quick jerks.

According to this invention the apparatus comprises a feeder for intermittently feeding stock from a supply reel along a predetermined path in which a portion of the stock is free to move in a direction transverse of the path, and a regulator intermediate the reel and feeder for maintaining uniform tension in the stock, the regulator comprising a guide bearing on said portion and means yieldingly pressing the guide in said direction, the aforesaid means including a chamber containing gas under pressure and an actuator responsive to said pressure for actuating the guide, whereby the guide can react quickly in response to rapid jerks of the feeder. Preferably the apparatus also comprises a gas reservoir communicating with the aforesaid chamber, the capacity of the reservoir being larger than that of the chamber, and means for maintaining the pressure in the reservoir approximately constant. In the preferred embodiment the aforesaid chamber is a cylinder and the actuator comprises a piston in the cylinder.

In a more specific aspect the apparatus comprises a constant feeder at one location along the aforesaid path, an intermittent feeder farther along the path, a portion of the stock between said feeders being free to move in a direction transverse of the path, and a regulator in said portion for maintaining uniform tension in the stock, said regulator comprising a guide bearing on said portion and means yieldingly pressing the guide in said direction, said means including a chamber containing gas under pressure and an actuator responsive to said pressure for actuating said guide, whereby the guide can react quickly in response to rapid jerks of said feeder.

For the purpose of illustration a typical embodiment of the invention is shown in the accompanying schematic view of a part of a machine for making wire binders for loose leaf books, which machine is disclosed and claimed in my copending application Ser. No. 772,158, filed Oct. 31, 1968, on even date herewith.

As disclosed in the aforesaid application the machine comprises an arm 1 which swings back and forth about a pivot 2 between the two positions shown in full and broken lines to wind wire W over a series of pins 3 which are progressively advanced into the path of the wire, the arm being oscillated by a rotor 4 through an eccentric 6 or other suitable means for converting rotary motion into oscillating motion. As the arm oscil-

lates in each direction the wire is jerked forward, as it reverses its direction the wire slacks off and as hereinafter explained the slack is taken up by the present invention so that the wire is kept taut all the time.

In the preferred embodiment the wire is fed from a reel 7 at a constant rate by a pulley 8 about which the wire makes at least one turn so as not to slip on the wire, the pulley being driven by a motor 9 through reduction gearing 11. From the pulley 8 the wire is pulled by oscillator 1 over a series of pulleys 12, 13, 14, 15 and 16 and thence between two rollers 17 and 18, the pulleys 13 and 15 floating in two loops 19 and 20 of the wire. As the oscillator moves from the position shown in the figure to midposition it has a backward component of movement and as it swings from midposition to side position it has a forward component of movement. Thus the feeder has alternate components of movement in opposite directions lengthwise of the path of the wire. The floating pulleys are journaled on one end of an arm 21 which is pivotally supported at 22. By a bracket 23 the arm 21 is connected to a piston 24 sliding in a cylinder 25 which is pivotally supported at 26. The cylinder 25 is connected to a chamber 27 which contains air or other gas and in which the pressure is maintained constant by a pressure regulating valve 28 connected to a suitable source of pressure.

From the foregoing it will be understood that with the oscillator 1 feeding the wire at an average velocity equal to the constant velocity of the feeder 8, as the oscillator slacks off the wire, the slack is taken up by the pressure in cylinder 25. By making the capacity of the reservoir much larger than that of the cylinder, the pressure in the cylinder is kept approximately constant as the piston moves back and forth and, by making the parts 13, 15, 21, 23 and 24 small and of light material, the tension on the wire may be kept uniform even when the oscillator jerks the wire at a frequency as high as 140 oscillations per second or higher.

It should be understood that the present disclosure is for the purpose of illustration only and that this invention includes all modifications and equivalents which fall within the scope of the appended claims.

I claim:

1. Apparatus for handling wire comprising a supply reel, a first feeder for continuously feeding wire from a reel, a second feeder for intermittently feeding wire from the first feeder along a predetermined path in which a portion of the wire is movable in a direction transverse of the path, the feeder having alternate components of movement in opposite directions lengthwise of said path, and a regulator intermediate the two feeders for maintaining uniform tension in the stock, said portion comprising a plurality of depending loops and said regulator comprising a roller floating in each of said loops, and means yieldingly pressing the rollers downwardly, said means including a chamber containing gas under pressure and an actuator responsive to said pressure for actuating said rollers, whereby the regulator can react quickly in response to rapid jerks of said feeder.

2. Apparatus according to claim 1 wherein said chamber is a cylinder and said actuator comprises a piston in the cylinder.

3. Apparatus according to claim 1 further characterized by a gas reservoir communicating with said chamber, the capacity of the reservoir being larger than that of the chamber.

4. Apparatus according to claim 3 further characterized by means for maintaining the pressure in the reservoir approximately constant.

5. Apparatus according to claim 1 further characterized by a common shaft for said rollers.
